UNITED STATES PATENT OFFICE.

GEORGE H. WHITTINGHAM, OF BALTIMORE, MARYLAND, ASSIGNOR TO MONITOR
CONTROLLER COMPANY, OF BALTIMORE, MARYLAND, A CORPORATION OF MARY-
LAND.

COMPENSATING THERMAL RELAY.

Application filed March 17, 1927. Serial No. 176,157.

This invention relates to a thermally operated overload relay, constructed so that the relation of the thermal device to the switch which it controls will not be affected by 5 changes in atmospheric temperature, and the opening of the switch will depend solely upon the heating effect of the current in the circuit to be controlled.

In carrying out the invention, I provide a 10 switch having a member normally biased toward closed position, a thermally responsive device controlled by a heating element, for moving said member to the open position, and a second thermally responsive device, af- 15 fected by atmospheric temperature only, for adjusting the position of said member, with respect to said first mentioned device, to compensate for corresponding adjustments of the latter, due to changes in atmospheric tem- 20 perature.

In the accompanying drawing,

Fig. 1 is a front elevation of the compensating overload relay;

Fig. 2 is a section on the line 2—2 of Fig. 25 1; and,

Fig. 3 is a top plan view of the relay.

Referring to the drawing, *a* and *b* indicate similar thermostat devices of the kind illustrated in my Patent Number 1,627,816; dated 30 May 10, 1927, each element comprising a bimetallic band 1, coiled helically into a tube. Brackets 2 and 3, secured to a suitable base 4 of insulating material, support the tubes at their upper and lower ends. The tubes are 35 open at their lower ends and secured within openings in the lower arms of the brackets. A plug 5 fits into the upper end of the tube of the device *a*, and is secured therein. A screw 6, in the upper arm of the bracket 2, 40 extends into a recess in the plug 5 and forms a pivot around which the plug may turn. The tube of the thermostat device *b* is similarly mounted. A disk 7, of insulating material, is attached to the plug 5 and this disk 45 extends back of a pivoted switch member *c* and is adapted to engage a projection *c'* on said member, to move the latter. A head 8, secured within the upper end of the device *b*, carries a laterally projecting arm 9 upon 50 which is mounted a contact 10, and the latter is normally engaged by a contact 11 on the switch member *c*. This switch member is provided with overturned ears 12, which are pivoted to a bracket 13, secured to the base 4.

A spring 14 constantly bears against one end 55 of the switch arm or lever and presses the other end, with its contact, against the contact of the arm of the thermal device *b*. The disk 7 of the device *a* is normally out of engagement with the projection *c'* of the switch 60 member *c*. A heating coil *d* extends upwardly within the device *a*, and the terminals of this coil are connected in a circuit *e*, which 65 it is the function of the device to protect. A circuit *f*, which the relay switch directly controls, extends through the switch arm *c*, contacts 11 and 10, and the arm 9 of the thermostat device *b*, thence through said device. It 70 will be understood that a switch *g* in the circuit *e* is normally held in closed position by 70 a coil *f'* in the circuit *f*, and that when the latter circuit is interrupted the switch will open the circuit *e*.

With the parts arranged as shown in the drawing, the operation is as follows: The 75 two thermal devices are affected alike by changes in atmospheric temperature, but only one of them, the device *a*, is affected by the heater in the circuit *e*. The current in the circuit *f* is so small as to be negligible 80 and it has no heating effect upon the device *b*. The bimetallic coils of the devices *a* and *b* are wound oppositely, as shown, and, being arranged on opposite sides of the switch arm *c*, in the illustration given in the drawing, 85 an increase in atmospheric temperature will cause the insulating disk 7 and the arm 9 to move forwardly or away from the base 4, and a decrease in atmospheric temperature 90 will cause the members to move backwardly or toward the base. As the switch arm *c* is constantly pressed against the contact carried by the arm 9, the circuit through the switch will be maintained during these 95 adjustments for atmospheric temperature, and the disk 7 will maintain a constant distance from the projection *c'* on the switch arm. Thus, in extremes of atmospheric temperature, the distance between the parts 7 and *c'* 100 will be maintained constant, providing the tube of the device *a* is not heated by current in the heating device *d*. When the current in the circuit *e* becomes excessive, or above a predetermined amount, for a short period, the tube of the device *a* uncoils and the disk 105 7 engages the part *c'* and moves the switch arm *c* away from the contact on the arm 9 of the device *b*, thus opening the relay cir-

cuit *f*, thereby de-energizing the coil *f'* and causing the switch *g* to interrupt the circuit *e*.

It will be seen that the thermostat device 5 *b* adjusts the switch members to compensate for changes in the position of the disk 7, carried by the device *a*, which may be caused by changes in atmospheric temperature, and that the device *a* will operate to open the 10 switch upon the occurrence of a predetermined overload current in the circuit *e*, without being affected by atmospheric temperature. The arm which supports the disk 7 is shorter than the arm which supports the 15 contact 10 in the illustration given in the drawing, because these arms are at different distances from the pivotal axis of the switch member *c*. If the arms were arranged at the same distance from the pivotal axis of the

switch member, of course, they would be made 20 the same length.

What I claim is:

In a thermally controlled relay, two thermally responsive devices, each comprising a metal helix fixed at one end and having a 25 laterally projecting arm at its opposite end, a movable switch member normally pressed against the arm of one of said devices, the arm of the other device being normally out of engagement with the switch member and 30 adapted to engage and move said member upon predetermined rise in temperature in said latter device, and electric heating means adjacent said latter device.

In testimony whereof I hereunto affix my 35 signature.

GEORGE H. WHITTINGHAM.
